IRONEE

George K. Parsons, Detroit, Mich.

Application April 14, 1931, Serial No. 530,118

6 Claims. (Cl. 68—9)

This invention relates to ironing machines, and more particularly to an ironing machine affixable to a washing-machine or the like, to secure its motive power from the drive shaft thereof.

5 It is an object of this invention to provide such an ironer which is of improved construction, but which nevertheless is relatively very light, and easily lifted and attached to or detached from a washing machine.

10 Another object of this invention lies in the provision of novel and effective but simple means for attaching the cover to the ironing roll.

Other objects and advantages will be apparent from the following description, wherein reference 15 is made to the accompanying drawings illustrating a preferred embodiment of my invention and wherein similar reference numerals designate similar parts throughout the several views.

In the drawings:

20 Figure 1 is a side elevational view showing my improved ironer attached to a washing machine of the type described in my co-pending application, Serial Number 530,117, filed on the 14th day of April, 1931.

25 Figure 2 is a top plan view of the same.

Figure 3 is a detail vertical longitudinal sectional view of my ironer, part of the operating handle being broken away.

Figure 4 is a detail top view thereof, partly in 30 plan and partly in section.

Figure 5 is an end elevational view looking in the direction indicated by the line and arrows 5—5 of Figure 3.

Figure 6 is an elevational view of the opposite 35 end of my improved ironer, with the gear casing cover removed.

Figure 7 is an enlarged detail sectional view of 40 my preferred form of clutch member for releasing a gear to stop the roll when the shoe is moved away by upward movement of the handle, and

Figure 8 is an enlarged detail cross section of the lock which I employ to fix the position of the shoe except when it is moved by the handle.

Referring now to the drawings: Across the top 45 of the washing-machine tub extends a supporting cross-bar 10, the details of construction of which are shown and described in my Patent 1,913,612, granted June 13, 1933. The cross-bar carries a downwardly extending elongated boss 11, Figure 50 1, upwardly through which passes an extension shaft 12, which is attachable to the driving shaft of the washing machine in a manner described in the aforesaid patent, the disclosure of which also shows that the supporting cross-bar is equipped with a socket surrounding the upper ex-

tremity of the extension shaft, which socket serves as a support for certain of the attachments affixable thereto. My improved ironer carries a downwardly extending sleeve portion 13 formed to accurately fit within the socket, and a locating pin 14, which fits within a suitable aperture in the cross-bar to position the ironer and prevent rotation thereof within the socket of the cross-bar; as shown in Figure 1. A vertical shaft 15 is journaled in and extends upwardly through the portion 13, and is slotted at its lower end to enable driving the same by the extension shaft 12, which carries a collar and cross pin at its upper end, as shown and described in the aforesaid co-pending application. A worm 16 is carried by and fast upon the shaft 15 near its top, as shown in Figure 5. A worm wheel 17, Figures 3 and 5, is drivable by the worm 16 and is affixed to the horizontal shaft 18, which extends through the tubular housing 19 and carries a gear 20 at its other extremity, within the gear housing 21, which gear housing also serves as a supporting frame. A cover 22 is suitably secured to the gear housing, as by screws 23.

The housing and supporting frame 21 rotatably support a roller 24 in the manner best shown in Figure 3. It will be seen that a tubular support 25 is rigidly carried by an elongated boss 26, formed integrally with the frame 21. The roll 24 is journaled upon the supporting tube 25, as at 27 and 28, and a shaft 29 for driving the roll extends through the tube 25, carrying a coupling member 30 at its end through which the roll may be driven. The coupling member 30 may be secured to the shaft by a set screw, as 35 75. The roll may be released at will from the driving shaft 29 by means of the pin 31, carried by the coupling member 30, which normally engages an aperture in the end plate 32 of the roll to drive the same. The pin 31 is normally held in driving engagement with the roll, with its end in the aperture in the end plate 32, by a spring-pressed ball detent 33 engageable in a circumferential slot 34 in the pin. When the pin is pulled outwardly, the roll is released, and 40 may remain stationary, which is frequently convenient in pressing. The roll driving shaft 29 is drivable by the gear 20 through the idler gear 36, and the gear 35, the idler being journaled on a pin 37 extending through the housing. The gear 35 is freely rotatable upon the shaft 29, but may be secured thereto to enable driving the roll by the clutch member 38, which is slidably splined on the shaft and formed with radially projecting teeth 39, adapted to engage com- 45 50 55 60 65 70 75 80 85 90 95 100 105 110

plementary inwardly projecting teeth 40, carried by the gear 35, as upon a ring 41 which may be riveted to the side thereof adjacent the clutch, as shown in Figure 7. The clutch is normally urged toward the engaged position by the button 42 carried by a spring-pressed plunger 43. The spring is designated 44.

Another tubular support 45 is carried by the housing behind the roll, as shown in Figures 4, 10 5, and 7, and serves as a support for a shoe 46, engageable against the roll, and an operating handle 47 for moving the shoe toward and away from the roll. As shown in Figure 5 the shoe is moved toward the roll as the handle is moved 15 downwardly and away when the handle is moved upwardly. The shoe is pivotally affixed to a crank 48, and its inner cylindrically concaved face is held in substantial alignment with the surface of the roll by the looped spring 49, which 20 urges the bottom of the shoe toward the roller.

To enable locking the shoe to prevent outward movement thereof when it has been moved inwardly by the handle to any desired position, the handle does not act directly upon the shoe, 25 but is secured to the shaft 50, which passes centrally through the tubular support 45 and actuates a lock, which in turn actuates the shoe through the tubular shaft 51. As shown in Figure 4, the shafts 50 and 51 and support 45 may 30 be arranged one within the other to conserve space; while the tubular construction of as many of the shafts and supports as possible used in my ironer, materially lightens the entire assembly. The shaft 51 acts upon the shoe-supporting crank 35 48 through the relatively stiff torsion spring 52, which enables the shoe to give slightly if material of uneven thickness is fed through the machine. The crank 48 is freely rotatable about the shaft 50, and is formed with an integral 40 sleeve portion 53, which extends into the tube 45, where it stops a spaced distance from an annular collar or sleeve member 54 rigidly carried by the end of the shaft 51. The torsion spring 52 is positioned within the space thus 45 formed and encircling the shaft 50, and is formed with angularly bent end portions 55, which extend outwardly in opposite directions parallel to the axis of the shafts and tubular support to engage suitable apertures in the sleeves 53 and 54.

50 The lock itself, which functions somewhat in the manner of an overrunning clutch, forms no part of this invention, but its construction is shown in Figure 8 and will subsequently be described in order that the operation of the entire device may be understood. It will be seen (note Figures 6 and 7) that the actuating portion, which is controlled by the operating handle 47 through the shaft 50, carries a cylinder cam 56 at its extremity within the gear housing. The 55 track of the cylinder cam moves a lever 57, integrally with which is formed a shifting yoke 58 for moving the clutch member 38. The cam is arranged so that when the handle is moved upwardly to move the shoe away from the roll, 60 the clutch member 38 is slid away from the gear 35 by the yoke 58, and the gear is accordingly released, so that the roll is no longer rotatable thereby.

As shown in Figure 7 the slot 78 within which 70 the yoke acts, formed in the periphery of the slidable clutch member 38, is wide enough to permit the yoke to move inwardly toward the gear all the way when the handle 47 is depressed without affecting the clutch except to free it. 75 It is then pushed into engagement by the spring

44 when the clutch teeth 39 and 40 are aligned.

As shown in Figures 5, 7 and 8, movement of the handle 47 rotates the members 59 within the lock casing, which is in the form of a ring 63 secured within the housing and arranged concentrically about the shaft 50 beside the cam member 56. The annulus 63 may be secured to the housing by screws, as 62. The members 59 may project integrally from the cam member 56 back into the area bounded by the ring 63. The shoe-actuating shaft 51 carries within the lock the disc 60, which may be formed with one or more peripherally cut away portions or slots 61. As shown in Figure 8, the bottom surfaces of the slots or cut out portions 61 are concentric with the periphery of the disc, except for a flattened portion 61', which enlarges the distance at that point between the bottom of the slot and the annulus 63. A ball or roller 64 is positioned between the disc 60 and the ring 63 in the inclined runway formed by part of the cut out portion of the disc. In the construction here shown a roller is used, which is normally wedged between the disc and the ring by the spring-pressed plunger 65, as shown in Figure 8. Forcing the shoe 100 away from the roll would tend to turn the disc in the direction of the arrow 66, which movement the rollers 64 resist by their wedging action, as will be readily apparent. If, however, it is desired to move the shoe away from the roll by 105 means of the handle, upward movement of the handle moves the members 59 in the direction of the arrows 67, and the members 59 release the rollers 64 by forcing them toward the larger part of the opening, after which continued movement 110 of the handle turns the disc in the direction of the arrow 66 to move the shoe away from the roll. When the shoe is moved toward the roll by means of the handle, the members 59 are moved in the opposite direction to that indicated by the arrows 67, and move the disc by engagement with the ends 68 of the slots in the disc. Such movement of the disc is not resisted by the rolls as friction then urges them toward the larger ends of the runways.

Rubber feet 69 may be secured to the outside of the gear housing, as shown in Figure 4, upon which the ironer may be stood when not in use.

The driving shaft of the washing machine to which my ironer is designed to be coupled in the 125 manner previously described, may be driven at varying speeds, a variable speed transmission being incorporated therein, the details of construction of which are disclosed in my co-pending application, Serial Number 530,117, filed on the 14th 130 day of April, 1931. Accordingly the rate of rotation of the roll 24 may be varied by means of the gear shift lever upon the washer, and when ironing simple pieces or flat work, the roll may be rotated much faster than ordinarily ironing machine rolls are driven, as in constant speed machines the rate of rotation of the roll must be slow enough for all purposes. The gear shifting lever and transmission housing are shown in Figure 1, designated 70 and 71 respectively. An 135 electrical heating element 72 may be positioned within the shoe as shown in Figure 5, extending longitudinally thereof adjacent the ironing surface. Electrical connection to the heating element may be provided by means of a flexible 140 insulated cord 76 of the usual style, the plug 77 of which may be inserted in any receptacle, although I preferably provide a receptacle for such purpose in one of the legs of my washing machine, as indicated in the aforesaid co-pending applica- 145

tion as well as in the drawings accompanying the present application.

The roll, which is formed of sheet metal, may be provided with a longitudinal groove 73, which 5 is partly closed by over-hanging edges, as shown in Figure 5. The cover may then be secured to the roll by means of a rod, rope, heavy seam, or any other suitable enlargement, which may be sewed to one end of the cover and slipped into the 10 groove from the end. The enlargement is of course of such size that it cannot be pulled radially outwardly between the over-hanging edges of the groove.

While it will be apparent that the illustrated 15 embodiment of my invention herein disclosed is well calculated to adequately fulfill the objects and advantages primarily stated, it is to be understood that the invention is susceptible to variation, modification and change within the spirit 20 and scope of the subjoined claims.

What I claim is:

1. In an ironing machine, a combined gear housing and support, a rotatable roll carried thereby, an ironing shoe extending adjacent the 25 roll, and means for moving the shoe toward and away from the roll at will, and yieldably maintaining it in desired spaced relation to the roll, comprising a tubular supporting member extending from the housing adjacent the shoe, a 30 hollow shaft extending therethrough and resiliently connected to the shoe to enable movement thereof, a central shaft extending through said hollow shaft and rotatable independently thereof, both of said shafts extending into the 35 housing, a handle carried by said central shaft adjacent the outer extremity of the tubular member, and means within the housing connecting said central shaft with the hollow shaft operative to resist movement of the hollow shoe- 40 carrying shaft away from the roll except when induced by actuation of the handle.

2. In an ironing device, a combined gear housing and support, gear driving means therein, a rotatable roll carried by the housing and driv- 45 able through said gears, an ironing shoe extending adjacent the roll, a handle for moving the shoe toward and away from the roll, a unitary tubular support for both the shoe and the handle carried by the housing, a shaft connected to the 50 handle and extending through said tubular support, means within the housing and connected to said shaft for controlling the roll-driving means upon movement of the handle, and means connecting the handle and shoe enabling move- 55 ment of the shoe by the same handle.

3. In an ironing device, a combined gear hous- 80 ing and frame member, a rotatable shaft carried by the housing and projecting thereinto and therefrom, a rotatable roll carried by said shaft outside the housing, a gear driving means for the roll within the housing, including a gear upon the roll shaft but normally freely rotatable thereon, a clutch member enabling securing the gear to the roll shaft, an ironing shoe extending adjacent the roll, supporting means for the shoe also carried by and projecting from the housing in substantially parallel relation to the roll, a handle for moving the shoe toward and away from the roll at will, a shaft connected to the handle and extending through the shoe support into the housing and means connecting the last mentioned shaft and the clutch for actuating said clutch upon movement of the handle, to thereby secure the gear to the shaft when the shoe is moved toward the roll, and to release the gear from the shaft when the shoe is moved away from the roll.

4. In an ironing machine, an ironing roll, an ironing shoe, a handle for moving the shoe to a 100 position at any desired distance, within limits, from the roll, clutch means for resisting movement of the shoe away from the roll except when induced by movement of the handle, and means including a releasing member for releasing the clutch upon movement of the handle to permit 105 free movement of the shoe in either direction thereby.

5. In an ironing machine, a roll, an ironing shoe, a handle for moving the shoe to any de- 110 sired proximity with respect to the roll, within limits, and means for resisting movement of the shoe away from the roll in any position to which it may be moved by the handle, and means connecting the handle and resisting means to release the latter upon movement of the handle in a 115 direction to move the shoe away from the roll.

6. In an ironing machine, a roll, an ironing shoe, a handle for moving the shoe to any desired proximity with respect to the roll within limits, a clutch member releasable upon actuation of the 120 handle in either direction but adapted to resist movement of the shoe away from the roll, means connecting the clutch to the shoe, and means connecting the handle to the clutch, one of said connecting means incorporating lost motion, 125 whereby movement of the handle in either direction first releases the clutch and then moves the shoe.

GEORGE K. PARSONS.
